CLAIM

The ornamental design for a light emitting diode lamp, as shown and described.

DESCRIPTION

FIG. 1 is a perspective view of a light emitting diode lamp showing the new design.

FIG. 2 is a front view thereof.

FIG. 3 is a rear view thereof.

FIG. 4 is a left side view thereof.

FIG. 5 is a right side view thereof.

FIG. 6 is a top plan view thereof, and bottom plan view being a mirror image of the top plan view.

FIG. 7 is an enlarged cross-sectional view taken along line 7—7 in FIG. 2 with the internal parts omitted, wherein the portions having the double slanted lines are transparent.

FIG. 8 is an enlarged cross-sectional view taken along line 8—8 in FIG. 2 with the internal parts omitted, wherein the portions having the double slanted lines are transparent; and,

FIG. 9 is an enlarged end-elevational view taken along line 9—9 in FIG. 2 with the internal parts omitted, wherein the portions having the double slanted lines are transparent.
